Primary Examiner—Mitchell Siegel

(74) Attorney, Agent, or Firm—Allan L. Harms

(57) **CLAIM**

I claim the ornamental design for a silt fence installing machine, as shown and described.

DESCRIPTION

FIG. 1 is a left rear perspective view of a silt fence installing machine showing my new design;

FIG. 2 is a front elevation thereof;

FIG. 3 is a rear elevation thereof;

FIG. 4 is a front end view thereof;

FIG. 5 is a rear end view thereof;

FIG. 6 is a top view thereof; and,

FIG. 7 is a bottom view thereof.
